DESIGN FOR A BATHING CAP

Franklin S. Klein, Malverne, N. Y.

Application November 23, 1938, Serial No. 81,305

Term of patent 14 years

To all whom it may concern:

Be it known that I, Franklin S. Klein, a citizen of the United States, residing at 59 Ocean Avenue, in the town of Malverne and State of New York, have invented a new, original, and ornamental Design for a Bathing Cap, of which the following is a specification, reference being had to the accompanying drawing, forming part thereof.

The figure is a side view of a bathing cap, showing my new design. The design is characterized by the ornaments on the side of the bathing cap, said ornaments being composed of brilliants arranged as shown; the opposite side of said bathing cap being of the same design.

I claim:

The ornamental design for a bathing cap, substantially as shown and described.

FRANKLIN S. KLEIN.
